LINE CLAMP

William L. Brownlee, Toutle, Wash.

Application September 26, 1938, Serial No. 231,649

2 Claims. (Cl. 24—136)

This invention relates generally to logging, and particularly to a line clamp.

The main object of this invention is to construct a clamp whereby a line may be fastened to a stump or tree without the use of spikes such as are commonly employed for that purpose when a guy line is fastened to the stump.

The second object is to so construct the clamp that it will automatically take up the grip on the hauling line.

The third object is to so construct the clamp that its elements will lie close to the periphery of the stump or tree.

The fourth object is to make the action of the wedging member reversible under tightening or loosening conditions of the line.

I accomplish these and other objects in the manner set forth in the following specification as illustrated in the accompanying drawing, in which:

Fig. 1 is a plan showing the device attached to a stump.

Fig. 2 is a section taken along the line 2—2 in Fig. 1.

Fig. 3 is a section taken along the line 3—3 in Fig. 1.

Fig. 4 is a side elevation of the device separated from the line.

Fig. 5 is a perspective view of the ferruled rope section.

Fig. 6 is a fragmentary view showing the interior of the rope engaging jaws.

Similar numerals refer to similar parts throughout the several views.

Referring in detail to the drawing, there is shown a back plate 10 having the converging sides 11 and 12, the side 11 having the flange 13 formed thereon and the side 12 having the grooved face 14 formed thereon adapted to conform with the strands of a cable 15.

Between the converging sides 11 and 12 is disposed a wedge 16 whose side 17 is grooved in a manner similar to the face 14, whereas, the edge 18 is slidable within the groove 19 formed behind the flange 13.

The plate 10 has a cut-out portion 20 in which is disposed a spring 21 which is secured by means of a pin 22 to the wedge 16 and by means of a toggle lever 23, it is held to either of the hooked projections 24 or 25, thereby enabling the spring 21 to urge the wedge 16 in either direction as desired.

It is desirable to provide a socket 26 at one end of the side 11 to receive the ferrule 27 of the short cable 28 whose other ferrule 29 is

seated in the eye 30 through which the cable 15 passes after it has encircled the stump 31. The end 32 of the cable 15 is attached to a spar tree or other object to be fastened while the end 33 of the cable 15 is attached to the cable winding 5 drum, not shown.

A hook 34 is formed on the side 12 for the purpose of holding the clamp against the stump under conditions when the line portions are approximately parallel in which case the hauling 10 action would tend to draw the clamp away from the stump. In use the hook 34 is simply used to hold a small line which encircles the stump 31. It is desirable to provide the ears 37 on the side 12 to hold the wedge 16 in position. 15

The operation of the device is as follows:

The end 32 of the cable 15 is passed around the stump 31 through the eye 30 to a point of fastening on the spar tree. The clamp plate 10 is then put into position on the cable 15 between the stump 31 and the end 33 of the cable 15. 20 The short cable 28 which projects from the eye 30 is then attached to the socket 26 of the member 10. A pull from the winding mechanism is then applied to the end 33 which causes the member 10 to move toward the stump 31 if the line portions 32 and 33 diverge as shown in Fig. 1. If they do not diverge, however, it is desirable to secure the member 10 to the stump 31 by means of a lashing passed around the stump 31 and secured to the hook 34. As the pull is exerted on the cable 15, the wedge 16 under the urging of the spring 21 takes up the slack so that whenever the pull ceases, the cable 15 is securely gripped between the wedge 16 and the clamp side 12. 35

When releasing the clamp, it is first necessary to reverse the pull of the spring 21 and then place a strain on the cable end 33 thereby immediately freeing the cable from the grasping 40 action of the device.

Obviously, any other form of means for holding the eye 30 toward the member 10 may be utilized without departing from the spirit of this invention.

I claim:

1. A line clamp having in combination a channel shaped member the sides of which converge, a wedge disposed within said channel adapted to hold a line between same and an adjacent side 50 of said channel, a spring adapted to selectively urge said wedge toward or away from a wedging position and an eye attached to one side of said body through which a line may pass after it is passed through said clamp and around a stump 55

for the purpose of holding said clamp toward said stump.

2. A line clamp having in combination an elongated channel shaped body, the sides of which converge, a wedge disposed between said converging sides, means for securing the converging end of said body against a stump and an eye at-

tached to one side of said body through which a line may pass from a spar tree to a stump and thence between the wedge of said clamp and an adjacent side of the channel, said wedge having a reversible spring element adapted to selectively urge said wedge in either direction. 5

WILLIAM L. BROWNLEE.
